(57) **CLAIM**

The ornamental design for a liner for a food holding well, as shown and described.

DESCRIPTION

FIG. 1 is a perspective view of a liner for a food holding well;

FIG. 2 is a left elevation view thereof;

FIG. 3 is a top view thereof;

FIG. 4 is a front elevation view thereof;

FIG. 5 is a right elevation view thereof;

FIG. 6 is a bottom view thereof; and,

FIG. 7 is a rear elevation view thereof.
